Primary Examiner — Richard Edgar*Assistant Examiner* — David Truong(74) *Attorney, Agent, or Firm* — Reinhart Boerner Van Deuren P.C.(57) **CLAIM**

The ornamental design for a toe plug of a roller skate, as shown and described.

DESCRIPTION

FIG. 1 is a side view of a toe plug of a roller skate in accordance with a first embodiment, the other side being a mirror image;

FIG. 2 is top view thereof;

FIG. 3 is a bottom view thereof;

FIG. 4 is a perspective view thereof;

FIG. 5 is a side view of a toe plug of a roller skate in accordance with a second embodiment, the other side being a mirror image;

FIG. 6 is a top view thereof;

FIG. 7 is a bottom view thereof; and,

FIG. 8 is a perspective view thereof.

The broken lines in the drawings depict portions of the toe plug of a roller skate that form no part of the claimed design.
